UNITED STATES PATENT OFFICE.

CARL J. LANDIN, OF BOSTON, MASSACHUSETTS.

PUMP.

Application filed January 4, 1921. Serial No. 434,954.

To all whom it may concern:

Be it known that I, CARL J. LANDIN, a citizen of the United States, and resident of Boston, county of Suffolk, State of Massachusetts, have invented an Improvement in Pumps, of which the following description, in connection with the accompanying drawing, is a specification, like characters on the drawing representing like parts.

10 This invention relates to pumps and particularly to hand pumps such as are used for pumping up automobile tires, although the invention is applicable to hand pumps designed for other uses.

15 One of the objects of my invention is to provide an improved hand pump which is constructed so that the handle and other projecting parts can be folded into parallelism with the pump cylinder thus reducing materially the amount of space required for storing the pump away.

In order to give an understanding of my invention I have illustrated in the drawings a selected embodiment thereof which will

25 now be described after which the novel features will be pointed out in the appended claims.

In the drawings:

Fig. 1 is a side view of a pump embodying 30 my invention.

Fig. 2 is a top plan view of the pump handle.

Fig. 3 is a section taken on the line 3—3, Fig. 2.

35 Fig. 4 is a section on the line 4—4, Fig. 3.

Fig. 5 is a sectional view through the lower end of the cylinder, said view showing the piston in section.

Fig. 6 is a section on the line 6—6, Fig. 5.

40 Fig. 7 is a fragmentary view showing a head, the lower end of the pump cylinder partly in section.

Fig. 8 is a perspective view of the head at the upper end of the piston rod.

45 Fig. 9 is a perspective view of the folding foot piece.

My improved pump is of the well known type which comprises a cylinder 1 having a piston 2 therein to which is connected a piston rod 3 that extends through the head 4 of the cylinder and has a handle secured thereto. The cylinder has at its lower end a head or block 5 to which the delivery pipe 6 is attached, said pipe communicating with the

lower end of the cylinder through a suitable 55 passage formed in the block 5.

The parts as thus far described are, or may be, all as usual in any hand pumps of this nature and form no part of my present invention.

One of the features of my invention relates to the handle at the upper end of the piston rod 3 and by which the pump is operated. In my invention this handle is a foldable handle so that when the pump is 65 not in use the handle may be folded into parallelism with the cylinder thus reducing materially the space required to store the pump.

It is within my invention to make the 70 handle a foldable one in a variety of ways. I prefer, however, the construction herein shown wherein the handle is made in two sections each of which is pivoted to a head at the upper end of the piston rod, means 75 being provided to lock the handle sections either in their operative position or in their folded position.

The two handle sections are indicated at 7 and 8 respectively and these are pivotally 80 connected to a head 9 secured to the upper end of the piston rod 3. The head 9 is disk shaped and is provided on each side with a rib 10, said ribs being herein shown as extending vertically. Each handle section 7 85 and 8 is formed at its inner end with a disk-like portion 11 which corresponds in size to the disk-like head 9 each head 11 being formed on its inner face with a groove 12 which fits the rib 10. The handle sections 7 and 8 are pivoted to the head 9 so that they can be swung from their operative position shown in full lines Fig. 1 into the position shown in dotted lines Fig. 1 and they are clamped in either of these two positions by 95 means of a clamping bolt 13 which also constitutes the pivot for said handle sections. This clamping bolt 13 extends through one of the heads 11, through the head 9 and screw threads into a boss 14 formed on the 100 other head 11. The clamping bolt 13 is provided with a knurled thumb piece 15 by which it may be turned. The grooves 12 in the handle sections are so placed that when the handle sections are in their operative 105 horizontal position shown in Fig. 1 said grooves receive the ribs 10 on the head 9 and if the clamping bolt 13 is tightened when

the handle sections are in this position they will become clamped firmly to the head thus making a rigid handle by which the pump may be operated. When it is desired 5 to fold the handle sections the clamping bolt 13 is loosened sufficiently to permit the handle sections to be swung down into the dotted line position Fig. 1 and when in this position the clamping bolt 13 may be again 10 tightened so as to hold them in their folded relation. If desired the head 11 of each handle section may have another groove 16 therein which receives the rib 10 when the handle sections are folded.

15 I have herein shown the knurled thumb piece 15 as being cup shaped and I have provided a spring 17 within said head which is normally held under compression. The advantage of the spring is that when 20 the clamping bolt is loosened the spring will tend to hold the parts from movement relative to each other until some force is applied to the handle sections to either fold them or swing them into their operative 25 position.

Pumps of this type are commonly provided with either a stirrup at their lower end or a foot piece on which the operator places his foot when the pump is being 30 used. In order to provide a pump which can be stored in a minimum space I propose to make the pump with a folding foot piece which can be folded into parallelism with the cylinder when the pump is not in use. My improved foot piece is shown at 35 18 and it is provided at its inner end with the lateral extension 19 which is received within a recess 20 formed in the block 5. The foot piece 18 is pivotally connected to 40 the block by means of a pivot pin 21 which extends through the extension 19 and is sustained at its ends in the side walls 22 of the recess 20. With this construction the foot piece can be placed in the full line position 45 Fig. 1, which is its operative position or can be folded into parallelism with the cylinder as shown in dotted lines Fig. 1. When the foot piece is in its operative position the wall 23 of the extension 19 rests 50 against the wall 24 of the recess 20, thus assisting in holding the pump firmly in its vertical position.

I have provided herein novel means for 55 yieldingly holding the foot piece in either its operative position shown in full lines, Fig. 1 or in its folded position shown in dotted lines Fig. 1. For this purpose the extension 19 is formed at one end with a locking projection 25 that is adapted to be 60 received in either one of two recesses 26 or 27 formed in one of the side walls 22 of the recess 20. The projection 25 and the recesses 26 and 27 have a corresponding shape. A spring device is provided for 65 yieldingly holding the projection 25 in

either recess 26 or 27 while permitting said projection to move out of either recess as the foot piece is turned about its pivot. This spring device is shown as a coil spring 28 which is situated within the extension 19 and which bears at one end against a shoulder 29 formed on the pivot pin 21 and at the other end bears against the wall 30 of the recess in the extension 19 in which the spring is received. Since the pivot pin 21 is firmly anchored in the head 5 the action of the spring 28 will be to hold the end of the extension 19 yieldingly against the wall of the recess 20 in which the depressions 26 and 27 are located. With this 75 construction the foot piece can be readily turned from the full to the dotted line position and when it is in the full line position the projection 25 will occupy the depression or recess 26 while when it is in the dotted line position said projection will occupy the recess or depression 27.

The piston which I employ is of the cup-washer type and I have provided novel means for always maintaining a proper contact between said washer and the walls of the cylinder. The cup-washer of the piston is indicated at 31 and it is backed by a metal washer 32 that is carried by the piston rod as usual. Said piston rod also 90 has another metal washer 33 thereon situated within the cupped-washer 31. In my present invention I provide a third washer 34 which is secured to the end of the piston rod by a suitable screw 35 and I employ a spacing-collar 36 between the washers 33 and 34. Situated within the flange portion 37 of the cup-washer is an annular member 38 of leather or some other material which is capable of expanding and situated within 95 this annular member 38 is a spring device which tends to expand it outwardly into contact with the flange 37. This spring device may conveniently be in the form of a spiral spring 39. The spring 39 acts through 100 the expansible ring or member 38 to maintain the flange 37 of the cup-washer in yielding engagement with the wall of the cylinder so that upon every down stroke 105 of the piston the cup-washer will act to 110 make a tight joint with the cylinder.

I may, if desired, provide the member 38 with an inclined slit 40 as shown in Fig. 6 which will more readily permit it to expand or contract.

I claim:

1. In a pump the combination with a cylinder, a piston therein and a piston rod, of a head at the end of the piston rod provided with a rib on each side, two handle sections pivoted to said head and having grooves to receive said ribs when said handle sections are in operative position, said handle sections being foldable into a position in parallelism with the piston rod, and means 125

to lock said handle sections in their operative position.

2. In a pump the combination with a cylinder, a piston therein and a piston rod, of a head at the end of the piston rod provided with a rib on each side, two handle sections pivoted to said head and having grooves to receive said ribs when said handle sections are in operative position, said

handle sections being foldable into a position in parallelism with the piston rod, and a clamping bolt extending transversely through said handle sections and head and by which the handle sections are locked in their operative position. 10

In testimony whereof, I have signed my name to this specification.

CARL J. LANDIN.
